UNITED STATES PATENT OFFICE.

WILLIAM RICHARDSON, OF SOUTH BENWELL, NEWCASTLE-UPON-TYNE, ENGLAND.

MEANS FOR SECURING BILLIARD-CUE TIPS.

1,274,599.

Specification of Letters Patent. Patented Aug. 6, 1918.

Application filed November 5, 1917. Serial No. 200,370.

To all whom it may concern:

Be it known that I, WILLIAM RICHARDSON, a subject of the King of England, residing at South Benwell, Newcastle-upon-Tyne, England, have invented certain new and useful Improvements in Means for Securing Billiard-Cue Tips, of which the following is a specification.

My invention has for its object an improved means for securing billiard cue tips without the aid of gelatin glue or other adhesive substances and in order that the invention may be clearly understood, I refer to the accompanying drawing, in which:—

15 Figure 1 shows a sectional elevation of the said means;

Fig. 2 shows a plan thereof, and

20 Figs. 3 to 6 show elevations of each of the several parts according to Fig. 1.

25 Similar parts are designated by like references throughout the views.

In carrying out my invention I make provision of a cue tip A of leather or other suitable material, a sleeve B which is split into two equal parts and provided with a V-thread on the inside, a ring C which is adapted to be pressed over the sleeve B, and finally an adapter D which, when screwed into the screw-threaded portion of the sleeve B, causes the V-shaped part of the latter to be pressed into the cue tip A thereby securely fastening said cue tip to the adapter D.

30 This adapter is conveniently provided with screw-threads in order to allow of its screwing onto a billiard cue. Thus, when an old tip has to be replaced by a new one, the user causes the split sleeve to be unscrewed by turning it toward himself, whereupon he

places the new tip between the V-shaped part of the sleeve B and, after having pressed 40 the ring C over the sleeve B and subsequent to the attachment of the latter to the adapter D in the manner previously described, the cue tip is ready for the purpose.

A spigot S on the adapter D fits into the 45 bottom part of the ring C and keeps the several parts in alinement.

I do not confine myself by making the split sleeve B as shown in the drawing, for by serrating the V-shaped part of same, it 50 would give a more secure hold of the leather tip A.

Having now fully described my said invention what I claim and desire to secure by Letters Patent is:—

55 In the herein described means for securing billiard cue tips, the combination, with a cue tip of leather, of a split sleeve of which one end is screw-threaded and the other end formed with a V-thread adapted to engage the said tip, a ring fitting over the screw-threaded portion of the split sleeve, and an adapter having a spigot which fits into the bottom part of said ring, the said adapter having at one end screw-threads 60 which screw into the split sleeve and screw-threads at the other end to receive the billiard cue, all substantially as and for the purpose set forth and shown.

65 In testimony whereof I have hereunto set 70 my hand in the presence of two subscribing witnesses.

WILLIAM RICHARDSON.
